VARIABLE ORIFICE EXTRUDER DIE

Frank M. Willis, Wenonah, N.J., assignor to E. I. du Pont de Nemours and Company, Wilmington, Del., a corporation of Delaware

Filed Jan. 19, 1962, Ser. No. 167,269

10 Claims. (Cl. 18—12)

This invention is concerned with an extrusion die and more particularly with a controlled variable die extruder and a controlled variable die extruder system.

In many types of extrusion, the control of the cross section of the extruded material is of prime importance. This is especially true in the production of extruded explosive cord wherein it is required that the cord shall have an exact weight/unit length. A problem encountered with the use of conventional fixed orifice dies is that various explosive formulations which are extruded through conventional dies grow in cross sectional area after they have passed through the die, making uniform cross sections impossible.

It has been determined that the final dimensions of the extruded explosive cord will vary depending upon (1) the extrusion temperature, (2) the extrusion pressure or rate, and (3) the physical characteristics of the explosive formulation being extruded. At present, for a given extrudable formulation and with fixed orifice dies, it is necessary to adjust either the extrusion temperature or pressure or both to obtain constant cross sectional dimensions. The extrusion rate is thus extremely slow and very impractical from a commercial standpoint.

As to the production of explosive cord having varying cross sectional diameter, no workable commercial means is known to the prior art for producing such tapered cord, save the tedious process of interchanging an infinite number of fixed orifice dies or the use of pulsation methods and devices.

It is, therefore, an object of the present invention to provide a variable orifice die.

Another object is to provide a variable orifice die capable of producing tapered extruded materials of varying cross sectional design.

A further object is to provide a controlled variable die extruder system.

A still further object is to provide means for producing extruded materials of desired cross sectional configuration and design.

Another object is to provide a device for the production of extruded explosive cord of controlled, tapering cross section.

Another object is to provide an apparatus for providing an extruded explosive cord of controlled cross sectional design and configuration.

These and other objects are accomplished by the instant invention which provides a variable extruder die and a variable extruder die system.

Generally, the extruder die comprises a support, twin cylinders rotatably mounted in rolling relationship on said support, at least one of said cylinders being provided with an orifice-defining, circumferentially extending groove of varying dimensions, drive means adapted to engage said cylinders, and means for feeding extrudable material communicating with said groove.

More particularly, this invention provides an extruder die comprising a housing, twin cylinders rotatably

2

mounted in rolling relationship in said housing, at least one of said cylinders being provided with an orifice-defining, circumferentially extending groove of varying dimensions, said cylinders being provided intermediate their ends with circumferentially recessed spur gearing, die positioning drive means engaging said spur gearing, means for feeding extrudable material communicating with said groove, and an outlet from said groove through said housing.

It is given that the twin cylinders have spur gearing machined thereon and that this spur gearing be recessed. This, however, simply represents a preferred embodiment since the gearing need not be recessed and since such gearing might well be present near each extremity of each cylinder. In the latter case, at least one of each pair of geared ends of the twin cylinders, as they are positioned in the housing, would be of greater diameter than the largest diameter of that cylinder having it.

By the term "orifice-defining" is meant that the groove or grooves, as the case may be, in one, or both, cylinders, defines an opening of a desired cross section adapted to transform the extrudable material entering the die from its shapeless form to a form having a cross section conforming substantially to that defined by the groove or grooves. In the case where each cylinder is provided with a groove, each cylinder is positioned within the housing such as to permit one groove to complement the other and thus define the orifice.

This invention also provides a controlled die extruder system comprising (A) an extruder die comprising a housing, twin cylinders rotatably mounted in rolling engagement in said housing, at least one of said cylinders being provided with an orifice-defining circumferentially extending groove of varying dimensions, said cylinders being provided, intermediate their ends, with recessed, circumferential spur gearing, die positioning drive means engaging said spur gearing, means for feeding extrudable material communicating with said groove, and an outlet from said groove through said housing, (B) take-up means adapted to receive extruded material from said die, (C) gear means rotatably engaging said take-up means, (D) a camshaft engaging said gear means, said gear means being adapted to provide a high reduction ratio from said take-up means to said camshaft, (E) an orifice-controlling cam mounted on said camshaft, said cam being provided with a programmed surface, (F) means for driving said gear and take-up means, (G) a precision regulator means connected to said die positioning drive means, (H) a cam-rider pivotally connected to said regulator means, said rider contacting the orifice-controlling surface of said cam and said rider being adapted to transmit variations therein to said regulator means, said regulator means being adapted to receive said transmission and to relay said transmission to said die positioning means for regulation of said extruder die orifice.

The cam used herein is machined, or so constructed, as to define the desired predetermined cord cross section with respect to the extruded length thereof, whether the cross section be of uniform or variable dimension, and to reflect this change on its outermost edge or along its circumference. The cam is "read" by the cam-rider and the reading is transmitted to the precision pressure regulator means.

The above-described system is adapted to the production of varying diameter, i.e., tapered, extruded material, the

cross sectional diameter of which can be tapered according to a predetermined pattern. The above system is easily modified to provide a control adapted to maintain the programmed cross section of the extruded material within given dimensional limits simply by inserting a dimension-sensing device in a position in the system wherein inspection of the extruded material after it has undergone maximum growth is provided. Such a device would then transmit dimensional variations which exceed preset tolerances directly to a pneumatic, or to some other suitably operated controller device which matches the measured cord dimension with the desired programmed dimension and makes any correction necessary. The correction made by the controller transmits the correction to the die positioning drive means to adjust the positioning of the die cylinders to compensate for any undesired variations in cross section.

The instant invention will be more readily understood by reference to the accompanying drawings.

FIGURE 1 shows the variable extruder die connected to a pneumatic positioner.

FIGURE 2 is a cross sectional cut taken along line AA' of FIGURE 1.

FIGURES 3, 4 and 5 show various cross sectional cuts of the die depicted in FIGURE 2.

FIGURE 6 depicts a system adapted for the production of variable diameter extrudable material.

FIGURE 7 shows various cross sections capable of being produced by virtue of the instant invention.

FIGURES 8 and 9 show several of the many possible groove configurations which can define the die orifice. Note is made of the fact that when two grooves are present, they are complementary, i.e., one is right-handed and the other left-handed.

FIGURE 10 shows the die cylinder bearings having opposed flat segments connected by a differential adjusting screw for adjusting and maintaining zero clearance between said cylinders.

Referring now to FIGURE 1 and to FIGURE 2 which is a cut along line AA' of FIGURE 1, metal breast plate 1 and metal butt plate 2 are seen as defining the die block or housing 3 wherein two parallel holes of equal bore designed to contain twin cylinders 4 and 5 are machined so that each hole is made to break through the other tangentially to provide no clearance between the cylinders 4 and 5 rotatably mounted in the housing 3. To be certain that the cylinders 4 and 5 cannot rub on the housing 3 the cylinders are provided with journal extremities 6 contained by two sets of paired sleeve bearings 7 and 8, machined slightly larger in diameter than the diameter of the cylinders 4 and 5. To insure that the bearings in a pair do not interfere with one another and that they are capable of keeping the cylinders 4 and 5 rolling together with no clearance, flat segments 9 (see FIGURE 10) are provided on their periphery. The paired bearings 7 and 8 are then positioned within the housing 3 so that, as between each pair, these flat segments 9 face each other. Each bearing is drilled and tapped through the flat segment 9 with left- and right-handed threads, respectively, and a differential adjusting screw 10 with left- and right-handed threads on either end is fitted into, and joins, each pair of bearings. The differential adjusting screw 10 is used to adjust the center-to-center distance between a given pair of bearings. Thus, the distance between the longitudinal surfaces of cylinders 4 and 5 may be easily adjusted to zero. Circumferentially, recessed spur gearing 11 is engaged by reciprocating double square rack drive 12 projecting from pneumatic die positioner 13 engages the spur gearing 11 on the cylinders to maintain rotational angular orientation of the cylinders. Thus, cylinders 4 and 5 are adapted to rotate simultaneously in opposite directions. Circumferentially extending grooves 14 and 15, of varying predetermined shape and dimensions, are machined in each of the cylinders. O-rings 16 are provided adjacent grooves 14 and

15 to prevent the flow of extrudable material into other parts of the housing 3. A cleaner follower 17 resiliently mounted in the housing (see FIGURE 3) is provided and so positioned in the housing 3, as to provide cleaning means for each of said grooves 14 and 15. To provide axial orientation of the cylinders 4 and 5 and of their complementary orifice-defining grooves 14 and 15, axial adjusting means 18 is mounted in the housing contiguous to the extremity of each cylinder to enable fine adjustment of the axial alignment of the grooves and to reduce the axial motion of both cylinders to zero. An outlet 31 in the housing 3 is provided to allow an exit for the extruded material 21.

FIGURE 3 is a cut along line BB' of FIGURE 2 and shows the circumferentially varying depth of the grooves 14 and 15 together with the positioning of cleaning followers 17 in the housing 3 and abutting the cylinder grooves.

FIGURE 4, which is a cut along line CC' of FIGURE 2, shows the engagement of the double square rack 12 with the spur gearing 11 of cylinders 4 and 5.

FIGURE 5, which is a cut along line EE' of FIGURE 3, shows the positioning of the axial alignment screws 18 contiguous to the paired bearings 7 and 8. Each of the alignment means 18 consists of a slotted eccentrically positioned metal head attached to a shank which fits in a hole drilled in breast plate 1 in a direction vertical radially from the center line of the axis of the corresponding die cylinder, said shank being held in fixed position by set screw 34.

FIGURE 6 is a schematic representation of a variable die extruder system of this invention. The die assembly 1 in FIGURE 6 is attached to pneumatic die positioner 13 with double square rack drive 12 engaging the spur gearing 11 of the cylinders 4 and 5 (see FIGURE 2). A source of material to be extruded and an extruder are positioned above the die-housing 3 and said material is channeled from the extruder to the die orifice by supply tube 20. The extruded material 21 coming from the die orifice is led through a dimension sensing device which is positioned in the system at a point beyond where maximum growth of the extruded material 21 has taken place. The extruded material 21 is then led through a traverse guide 32 and attached to rotating drum 22 which is driven by a tension motor (not shown). The axle 28 of the drum 22 engages reduction gear means from which a rotatable camshaft 24 extends. A cam 25 secured to the camshaft 24 is provided with a programmed surface on its edge which is continuously engaged by cam-rider 27 attached to lever 33 which is pivotally mounted under some tension to the precision pressure regulator. A power pressure regulator, or power source, is connected to the precision pressure regulator and both of these are connected by flexible connections 29 to the pneumatic die positioner 13. A pneumatic controller is connected to the dimension sensing device through line 35 and is inserted in the system between the precision pressure regulator and the pneumatic die positioner.

FIGURE 7 depicts some of the various cross sectional configurations of the extruded material which are possible. Each is produced by the corresponding groove or complementary grooves machined into the twin cylinders 4 and 5. Of course, many other cross sectional shapes are possible and those depicted are only representative.

FIGURE 8 shows a cut away view of twin cylinders having unsymmetrical circumferentially extending shaping means 14 and 15 forming the orifice 30. In this figure one cylinder carries a projecting tongue which is in axial alignment with a groove in its oppositely paired cylinder to give a grooved cross section to the extrusion (see FIGURE 7). For a cylinder of such a design a mating groove is machined in the housing formed by plates 1 and 2 so that the tongue of the rotatable die forming cylinder does not engage the surface of the housing within the limits of rotation of said die forming cylinder.

FIGURE 9 shows a cut away view of twin cylinders, only one of which has provided thereon a circumferentially extending groove 14. Together they define the orifice 30.

FIGURE 10 shows a pair of sleeve bearings 7, each having a flat segment provided thereon and each provided with a threaded bore 23. Differential adjustment screw 10 provided with right- and left-handed threads is adapted to be received by each member of the paired bearings to adjust their center-to-center distance. Hexagonally faced surface 19 permits access of a wrench for adjusting screw 10.

In actual operation, the die assembly of FIGURE 1 may be a part of a system similar to that depicted in FIGURE 6. Material to be extruded is forced by a conventional extruding means such as a ram type or screw type extruder through the orifice defined by the complementary grooves 14 and 15 in twin cylinders 4 and 5, and out through outlet 31 in the housing 3. The double square rack 12 extends through the housing and engages the spur gearing 11 of the cylinders 4 and 5 and is driven by the pneumatic positioner 13 which causes the cylinders to rotate in clockwise, counterclockwise directions respectively. The O-rings 16 positioned on either side and adjacent to the grooves 14 and 15 insure that material to be extruded is confined to a zone above the die orifice. The cleaning followers 17, which are optional, clear the respective grooves 14 and 15 when the cylinders 4 and 5 are made to rotate by die positioner 13. Signals transmitted from the precision pressure regulator to the pneumatic positioner 13 cause the pneumatic positioner 13 to move the reciprocating double square rack 12 which in turn causes rotation of the cylinders 4 and 5. This changes the dimensions of the orifice defined by orifice-shaping rolls 4 and 5. The extruded material 21 is fed through a dimension sensing device which is positioned in the system at a point wherein maximum growth of the extruded material 21 has taken place. The dimension sensing device is preset to record the variations in the cross sectional diameter of the extruded material. These variations are transmitted to the pneumatic controller which matches the measured dimensions with the desired program dimension and makes the necessary correction in the signal transmitted to the pneumatic positioner 13 thereby maintaining desired dimensions of the cord. The extruded material, after passing through the dimension sensing device, is received by a drum or mandrel 22 which is rotated by a constant tension mechanical motor (not shown) which is adjustable and provides constant tension on the extruded material 21. As the material is extruded, each revolution of the mandrel or drum 22 provides an exact measure of the extruded length. The drum or mandrel 22 is mounted on an axle 23 which is connected to a gear means, e.g., to a worm and wheel gear. A camshaft 24 engaging the gear mechanism has, mounted thereon, a circular cam 25 having a predetermined set program cut into its circumference. As the mandrel or drum 22 rotates, the axle 23 is driven into the reduction gearing which has a reduction ratio such that a number of revolutions of the axle 23 are required to obtain one revolution of the camshaft 24 on which the circular cam 25 is mounted. The variations in the programmed circumferential surface of the cam 25 are transmitted through a cam-rider 27 and lever arm 33 to a precision pressure regulator which adjusts the control pressure to the die I by transmitting signals to the pneumatic positioner 13 which in turn controls the positioning of cylinders 4 and 5 and thus the die orifice defined by grooves 14 and 15.

Thus, the cross sectional dimensions of the extruded cord are controlled according to a predetermined program machined into the control surface of the circular cam and are continuously adjusted within predetermined tolerances. A continuous extruded cord of substantially uniform cross section is produced, or optionally the ex-

truded cord has a predetermined tapered cross section, the taper appearing periodically in a head-to-tail, tail-to-head relationship as the dies are rotated by rack drive 12 from a first position to a second position in one direction, and then are reversed to the first position in conformance with the preset program. The dimension sensing device operates simultaneously to maintain tolerance limits on the dimensions of the tapered cord. Both the dimension sensing device and the pneumatic controller can be omitted from the system and variable diameter extruded material will still be produced; however, in such a situation exact control of the fluctuations in the diameter of the extruded material will be missing. It is understood that while a pneumatic controller is preferred in this system, other controllers well known to the art may be substituted and may provide suitable replacements.

Among the many dimension sensing devices which could be inserted in the above-described system to provide the desired modification, three examples offering excellent results are:

(A) A pneumatic gage device which measures diameters or changes in diameter by the pressure drop of air flowing through orifices directed toward the measured diameter and the gage could be defined as the dimensional sensing device. It would be used to continuously sense exact diameter as the extruded cord passed through the device. Variances in the cord diameter would be sensed as pressure variations and would be converted to a die correction signal transmitted to a pneumatic controller.

(B) A pair of rollers mounted on a cantilever arm, the pivot of which is connected to a pneumatic position sensing device, could be adapted to having the extruded cord pass between the rollers, i.e., engaging both rollers, as it proceeded to the take-up means. Variations in diameter would then be transmitted to a pneumatic controller which, in turn, would correct the die positioning drive means accordingly.

(C) A television camera, using close-up lens attachments, could be positioned to project a large image of the diameter of the extruded cord on a television monitor screen. Variations from the desired diameter would be sensed as "go" or "no go" signals which would, through a controller, adjust the variable extruder die.

It is necessary that the left- and right-handed paired cylinders rotate together in an exact angular relationship so that the orifice defined by the grooves or groove and alternate die-forming structure will maintain the desired cross section configuration. Thus, the parallel holes of the housing which contain the cylinders are equally spaced in the housing. For proper operation, the cylinders must be positioned and held to provide no clearance between their contacting longitudinal periphery. To accomplish this, the parallel holes in the die housing are machined so that they are each breaking through the other tangentially. This is accomplished by keeping the parallel center-to-center distance exactly equal to the diameter of the cylinder while each bore of the parallel holes is several thousandths larger. To be certain that the cylinders do not rub on the housing, the sleeve bearings are machined slightly larger in diameter than the cylinders and slightly smaller than the diameter of the holes. Axial alignment of the die-forming surfaces is provided, as mentioned above, by axial alignment means mounted in the housing contiguous to the extremities of each cylinder. Clearance between the cylinders is controlled by the adjusting screw 10 inserted between each pair of sleeve bearings. The mating groove or other shaping surface machined in each of the twin cylinders extend circumferentially and are of varying dimensions. Preferably, they extend from substantially zero dimensions at zero degrees rotation to maximum dimensions at about 180° of cylinder rotation. The depth of the circumferentially extending groove can vary from substantially zero to a depth substantially equal to the radius of the cylinder containing it. This depth will be governed to some ex-

tent by the composition of the cylinder since with a soft construction material in the cylinder, strength might be sacrificed in providing a groove of such depth as would amount to one-half of the diameter of the cylinder.

The pneumatic positioner shown in FIGURE 1 is produced by the Cono-flow Corporation. It is capable of linearly positioning any device to very precise tolerances. The power source is 100 p.s.i. air pressure and controls to a varying 0-15 p.s.i. air signal. The control air actuates the positioning mechanism with a feed back balance which forces the piston to travel to exactly the position called for by the control air signal. This device represents a mechanism which is preferred, yet it is by no means limiting since other suitable devices could be substituted for it to provide the same function.

For the proper operation of the die at normally high extrusion pressures (e.g., 1000 p.s.i.), it is necessary that the cylinders rotate together with essentially no clearance between their cylindrical surfaces. As mentioned earlier, this is accomplished by machining the parallel holes in the die housing so that they each break through the other tangentially. The sleeve type bearing with differential adjusting screw keeps the cylinder properly positioned in the hole of the die housing.

The precision pressure regulator and the power pressure regulator which is the power source are easily understood as used herein. Conventional pressure regulators, or reducing valves as used herein, are simply devices which take supplied air pressure (generally 100 to 125 p.s.i.g.) and reduce it to the desired working limits. The precision control pressure regulator is designed to operate at the conventional pneumatic control range of 3 to 15 p.s.i. Through this range, the regulator is extremely sensitive and accurate. The power pressure regulator is designed for a wider range (20 to 100 p.s.i.), and is a less accurate pressure regulator which supplies the power cylinder air pressure to the precision pressure regulator and cushions air pressure.

The variable diameter die and the extruder system are especially adapted to the extrusion of explosive cord; however, they would be operable in other than explosive service. For example, they might be used in extruding synthetic materials, i.e., nylon, etc., in the form of tapered filaments. A similar die which would be operated in an oscillating manner could vary the diameter from a preset lower limit to a preset upper limit. It would also be possible to use a piercing mandrel for producing tubings which would have tapering features of O.D., I.D., with either dimension constant, or both changing. Such a piercing mandrel could be mechanically integrated to the roll adjustment or independently controlled through its own mechanical adjusting system.

The invention has been described in detail in the foregoing; however, it will be apparent to those skilled in the art that many variations are possible without departing from the scope of the invention. The intent is, therefore, to be limited only by the following claims.

What is claimed is:

1. An extruder die comprising a support, twin cylinders rotatably mounted in rolling relationship in said support, at least one of said cylinders being provided with an orifice-defining, circumferentially extending groove of varying dimensions, die positioning drive means adapted to engage said cylinders, and means for feeding extrudable material communicating with said groove.

2. An extruder die comprising a housing, twin cylinders rotatably mounted in rolling relationship in said housing, at least one of said cylinders being provided with an orifice-defining, circumferentially extending groove of varying dimensions, said cylinders being provided, intermediate their ends, with circumferentially recessed spur gearing, drive means engaging said spur gearing, means for feeding extrudable material communicating with said groove, and an outlet from said groove through said housing.

3. The device of claim 2 wherein each of said cylinders is provided with a complementary orifice-defining surface, and wherein said surfaces vary from substantially zero dimensions at 0° of cylinder rotation to maximum dimension at about 180° of cylinder rotation.

4. The device of claim 3 wherein O-rings are mounted on said cylinder adjacent to and on either side of, said orifice-defining surfaces for limiting the flow of extrusion material.

5. The device of claim 4 wherein each cylinder is provided with journal extremities; wherein four sleeve bearings are mounted in said housing, each of said bearings being adapted to receive one of said journal extremities, and each of said sleeve bearings being provided with an axial flat segment on its periphery; and wherein each pair of sleeve bearings is positioned in said housing with said flat segments facing each other, and adjusting means are provided to regulate the center-to-center spacing between said bearing pairs.

6. The device of claim 5 wherein axial alignment means are mounted on said housing, said axial alignment means contacting each extremity of said cylinders to provide axial alignment of said die-forming surfaces.

7. In an extrusion system providing controlled cross sectional dimensions, an extrusion die comprising a housing, twin cylinders rotatably mounted in rolling relationship in said housing, at least one of said cylinders being provided with an orifice-defining, circumferentially extending groove of varying dimensions, said cylinders being provided, intermediate their ends, with circumferentially recessed spur gearing, drive means engaging said spur gearing, means for feeding extrudable material communicating with said groove, and an outlet from said groove through said housing.

8. In an extrusion system having a preset programming device and an automatic die positioner, a die comprising a housing, twin cylinders rotatably mounted in rolling relationship in said housing, at least one of said cylinders being provided with an orifice-defining, circumferentially extending groove of varying dimensions, said cylinders being provided, intermediate their ends, with circumferentially recessed spur gearing, drive means engaging said spur gearing, means for feeding extrudable material communicating with said groove, and an outlet from said groove through said housing.

9. A controlled variable die extruder system comprising

(A) An extruder die comprising a housing, twin cylinders rotatably mounted in rolling relationship in said housing, at least one of said cylinders being provided with an orifice-defining, circumferentially extending groove of varying dimensions, said cylinders being provided, intermediate their ends, with circumferentially recessed spur gearing, drive means engaging said spur gearing, means for feeding extrudable material communicating with said groove, and an outlet from the said groove through said housing,

(B) Take-up means adapted to receive extruded material from said die, said take-up means being provided with an axle therethrough,

(C) Gear means engaging one extremity of said axle,

(D) A camshaft engaging said gear means, said gear means being adapted to provide a high reduction ratio from said axle to said camshaft,

(E) A cam mounted on said camshaft, said cam being provided with a programmed surface,

(F) Means for driving said gear and said take-up means,

(G) A precision pressure regulator connected to said die positioning drive means,

(H) A cam-rider connected to said regulator means, said rider contacting said cam surface and being adapted to transmit variations in said surface to said regulator means, said regulator means being adapted to receive said transmissions and to relay said trans-

missions to said die positioning means for regulation of said die orifice.
 10. The system of claim 9 wherein a transmission guide is inserted adjacent to said take-up means to position the extruded material on said take-up means.
